UNITED STATES PATENT OFFICE.

BENJAMIN FRANKLIN DU BOIS, OF NEW YORK, N. Y.

DESIGN FOR A SIDE-BAR SPRING.

SPECIFICATION forming part of Design No. 29,579, dated November 1, 1898.

Application filed December 18, 1896. Serial No. 616,200. Term of patent 14 years.

To all whom it may concern:

Be it known that I, BENJAMIN FRANKLIN DU BOIS, a citizen of the United States, residing at New York, in the county of New York and State of New York, have invented and produced a new and original Design for Side-Bar Springs; and I do hereby declare the following to be a full, clear, and exact description of the same, reference being had to the accompanying drawings, forming a part thereof.

The invention relates to a new and original design for vehicle-springs; and it is embodied in the structure shown in the accompanying drawings, wherein—

Figure 1 is an elevation of the spring embodying my design, and Fig. 2 is a cross-section on the line $\alpha\alpha$ of Fig. 1.

The design, as depicted in the accompanying drawings, consists, essentially, of a long spring having a central body portion A, which is oval in cross-section, as shown, while the

portions on opposite ends of the body are bent down on gradual curves, tapered, and flattened, as at B. The extreme end portions 25 of the spring are curved upward and then backward and down, the radius of the curve decreasing and the end terminating in a ring C.

The essential feature of the design is the 30 long-shape spring having the oval body, tapered flat ends, and the curved extremities, as shown and described.

Having thus described the invention, what I claim as new, and desire to secure by Letters 35 Patent, is—

The design for a spring substantially as shown and described.

In testimony whereof I affix my signature in presence of two witnesses.

BENJAMIN FRANKLIN DU BOIS.
